UNITED STATES PATENT OFFICE

2,495,990

SLACK ADJUSTER

William J. Sockell, Raleigh, N. C.

Application June 18, 1948, Serial No. 33,759

4 Claims. (Cl. 74—503)

1

This invention relates to a novel slack adjustor for brake mechanism of railway rolling stock, particularly freight cars and which is capable of being used in connection with either air or hand brakes to compensate for wear on the brake shoes, brake heads and brake beams.

A primary object of the present invention is to provide a slack adjustor for accomplishing the aforescribed results, which is of extremely simple construction and capable of being readily applied to brake mechanisms of railway cars and by the use of which accurate adjustments of the slack can be accomplished.

Another object of the invention is to provide a slack adjustor capable of being readily released for resetting in the event that the brakes have been set too tight.

Another and particularly important object of the invention is to provide such a device which is capable of being adjusted or released without the operator being required to go beneath the car and which can be quickly and easily assembled or disassembled for replacing a broken part and which can be very readily applied to or removed from a railway car.

Various other objects and advantages of the invention will hereinafter become more fully apparent from the following description of the drawing, illustrating a presently preferred embodiment thereof, and wherein:

Figure 1 is a side elevational view showing the slack adjustor in an applied position;

Figure 2 is an enlarged cross sectional view taken substantially along a plane as indicated by the line 2—2 of Figure 1;

Figure 3 is a sectional view taken substantially along a plane as indicated by the line 3—3 of Figure 2, and

Figure 4 is an enlarged horizontal sectional view taken substantially along a plane as indicated by the line 4—4 of Figure 1.

Referring more specifically to the drawing, the novel slack adjustor in its entirety is designated generally 5 and includes a bracket 6 having a horizontal flange 7 which is adapted to be disposed beneath the center sill 8 of a railway car, such as a freight car, not shown, and secured thereto by suitable fastenings such as rivets 9. The bracket 6 is provided with a depending hanger portion or wall 10 which depends from one edge of the flange 7 and which is turned outwardly and back upon itself to form a wall 11 which terminates at its upper, free edge substantially below the level of the upper end of the wall 10. The walls 10 and 11 are connected

at their lower ends by an integral bottom portion 12.

A rack bar, designated generally 13 is slidably supported by the bracket 6 between the walls 10 and 11 and on the bottom 12 and extends to substantially beyond both ends of said bracket 6 and is provided at one end thereof with a handle 14 and has an integral eye 15 at its opposite end. The upper edge of the intermediate portion of the rack bar 13 is provided with teeth 16 all of which face in the same direction and each of which includes a substantially upright shoulder 17 which faces toward the eye 15 and an inclined opposite edge 18 which faces in the opposite direction.

The walls 10 and 11 are provided with aligned openings 19 through which extends a headed pin 20. The pin 20 extends loosely through an opening of a pawl 21 which is disposed between the bracket walls 10 and 11 and which extends from the pin 20 in a direction toward the handle end of the rack or slack adjustor bar 13. The free end of the pawl 21 is adapted to engage between adjacent teeth 16 and against one of the upright sides or shoulders 17 to prevent the rack bar 13 from sliding from left to right of Figures 1 and 3. A pin 22, corresponding to the pin 20 is similarly mounted in the walls 10 and 11 in longitudinally spaced relationship to the pin 20 and at substantially the same level for pivotally supporting a tumbler 23 having a bottom edge portion 24 which normally rests upon a portion of the upper edge of the pawl 21 for holding the free end of said pawl in engagement with the teeth of the bar 13. The tumbler 23 is also provided with a recessed bottom edge portion 25 into which a portion of the upper edge of the pawl 21 which is located adjacent its free end is movable as said pawl is swung upwardly to permit the free end of the pawl to rise sufficiently to clear the teeth 16 but for positively limiting the swinging movement of the pawl. The pins 20 and 22 are detachably retained in engagement with the bracket 6 by cotter pins 26. The front wall 11 is provided with an opening 27 sized to readily accommodate the finger and so that the operator can insert a finger between the teeth 16 and pawl 21 for lifting the free end of the pawl to release the slack adjusting bar 13 so that it can move freely from left to right.

The eye 15 of the bar 13 is connected to the free end of one lever of a conventional railroad car brake mechanism, as indicated at 28, by a clevis 29 which loosely engages the eye 15 and a pin 30 which extends through the legs of the

clevis 29 and through said free end of the brake lever and which is retained in an applied position by a cotter pin 31.

From the foregoing it will be readily apparent that the handle 14 can be manually grasped for moving the slack adjusting bar 13 from right to left of Figures 1 and 3 for taking up slack in the brake mechanism and when the bar 13 is thus moved the bottom edge of the free end of the pawl 21 will ride over the cam surfaces 18 of the teeth. As previously stated, the pawl 21 can be lifted by inserting a finger through the opening 27 for permitting the bar 13 to move from left to right for increasing the slack or loosening the brakes. The teeth 16 are located sufficiently close together so that a very accurate adjustment of the slack can be accomplished and in the event that the brakes are set too tight, a very slight movement from right to left of the bar 13 will permit the pawl 21 to be disengaged from the teeth 16 for releasing said bar 13.

Various modifications and changes are contemplated and may obviously be resorted to, without departing from the spirit or scope of the invention as hereinafter defined by the appended claims.

I claim as my invention:

1. A slack adjustor for brake mechanisms of railway cars comprising a bracket adapted to be secured to a car sill, a brake lever actuating slack adjusting bar extending reciprocally through said bracket and supported non-rotatably thereby, said bar being provided with a longitudinally disposed series of teeth in one surface thereof, said teeth having corresponding shoulders all facing in one direction and inclined cam surfaces all facing in the opposite direction, a pawl pivotally mounted in said bracket and having a free end engaging between adjacent teeth of said bar and against one of said shoulders to retain the bar against movement in the first mentioned direction, and a tumbler pivotally supported by the bracket and engaging on a portion of the upper

edge of the pawl for retaining the free end of the pawl in engagement with the teeth of the slack adjusting bar.

2. A slack adjustor as in claim 1, said pawl and tumbler being disposed between spaced, substantially parallel walls of the bracket, one of said walls being provided with an opening adapted to accommodate the finger for insertion between said teeth and the pawl for lifting the pawl out of engagement with the teeth to permit the adjustor bar to be displaced in said first mentioned direction.

3. A slack adjustor as in claim 1, said tumbler having a pivoted end disposed above the free end of the pawl to limit the upward movement of the pawl and being provided with a recessed portion for accommodating the free end of the pawl when the latter is swung upwardly and out of engagement with said teeth.

4. A slack adjustor as in claim 1, said bar having a handle at its opposite end adapted to be manually grasped for displacing said bar through the bracket in said last mentioned direction, and the free end of the pawl being adapted to ride over the cam surfaces of the teeth during such movement of the slack adjusting bar.

WILLIAM J. SOCKELL.
